UNITED STATES PATENT OFFICE.

CLEMENT H. RITZLER, OF NEW BUFFALO, MICHIGAN.

RAILWAY TIE.

Application filed July 26, 1921. Serial No. 437,582.

To all whom it may concern:

Be it known that I, CLEMENT H. RITZLER, citizen of the United States, residing at New Buffalo, in the county of Berrien and State of Michigan, have invented certain new and useful Improvements in Railway Ties, of which the following is a specification.

The invention has reference to railway ties and particularly to ties of the combined steel and wood type.

An object of the invention is to provide an improved form of tie having rail-supporting blocks insertable at opposite ends and a gravel filling space inwardly of the supporting ends and on the underside to enable the tie to become embedded in its place.

An additional object is to provide a railway tie of simple and inexpensive construction and embodying a main body portion, of practically indestructible material forming the tie proper, and supporting blocks to fit the tie, said blocks being removable when necessary to repair the tie or to be replaced by new blocks.

Various other objects and advantages of the invention will become apparent during the continuance of the following description.

30 In the drawings:—

Figure 1 is a top plan of the improved railway tie.

Figure 2 is a bottom plan thereof.

Figure 3 is a central, longitudinal section 35 thereof, and,

Figure 4 is a vertical cross section through the center of the tie.

The tie embodies an elongated metallic casing 10 having the tubular ends 11 and 12 closed at their inner end by plates 13 and 14 extending vertically of the tie as shown. Each plate is provided at the side with a securing flange 15 by means of which it is fastened to the side wall 16 of the tie by means of rivets or other suitable fastenings 17. These plates, it is to be noted, are relatively spaced so that they provide, in conjunction with the top and sides of the tie, a hollow or cavity 18 at the central portion of the tie and open at the under side thereof. The purpose of having the center of the tie open at the bottom is to enable gravel to fill the space when the tie is embedded in its place so that the latter will be firmly held 55 in its position in the road-bed; the gravel aside from providing anchoring means for

the tie serves also to reinforce the same by adding to the solidity of the structure and making the same more compact and stable.

The ends of the ties are filled with supporting blocks of wood or other suitable material, as indicated at 19, these blocks serving to receive the spikes by which the rails are fastened in place. These blocks are manufactured to fit the tie and slip in at the ends, 60 being stopped at the proper distance by the vertical walls 13 and 14.

Inserted through each plate 13 and 14, shank first so that the headed end is at the inner hollow portion of the tie, is a securing 70 bolt 20 extending longitudinally through block 19 to the end of the tie and having a nut 21 on its exposed end whereby the block may be fastened securely in place. Whenever a block becomes worn or impaired to 75 such an extent that its usefulness is at an end, it may be readily removed by unloosening nut 21 and withdrawing the block from the tubular end of the tie.

To facilitate the removal and insertion of 80 the blocks, the latter are each provided with a longitudinally extending bore 22 for the reception of bolt 20 and to prevent the exposure of the outer ends of the blocks to the elements, end shields in the form of metallic 85 plates 23, are provided, which fit into the tubular ends of the tie and are retained in place over the ends of the block by means of the securing nut 21 as clearly shown in Figure 3 of the drawing. 90

Each tubular end has its upper surface provided with a transversely extending opening or cut-out through which a portion of the supporting block is exposed as indicated at 24. The sides of the openings or cut-outs are spaced apart sufficiently to accommodate the base flange of the rail together with the necessary spikes. In attaching the rail, the spikes are driven into the wood blocks upon which the rail rests so as 100 to fasten the latter directly thereto, the wooden blocks providing a sufficiently yieldable support for the rails as to uphold the latter firmly but not too rigidly under the stresses and strains of rolling stock passing thereover. In addition the metal body portion or sheath provides a practically indestructible tie structure which is lasting and durable and which enables repairs to be made conveniently and without material alteration or disturbance of the track since 105 it is possible to readily replace worn blocks 110

with new ones by merely removing the spikes and slipping the blocks in place at each end of the tie, it being unnecessary to disconnect the rail which extends crosswise of the tie 5 and in its proper place in the cut-outs.

From the foregoing it is believed that the advantages and novel features of my invention will be readily understood and therefore further detailed description is deemed unnecessary.

What is claimed is:—

A railway tie having a hollow central portion open at the bottom to provide a gravel space, an outer tubular end-portion in line 10 with the gravel space, plates depending ver-

tically from the upper wall of the tie and closing the inner terminals of the tubular ends, a bolt carried by each of said plates and projecting longitudinally through the adjacent end of the tie, a supporting block 20 insertable in each tubular end and having a longitudinally extending central bore to receive the shank of the said bolt, said block having a portion exposed by openings in the top of the tie to receive a rail, and means engageable with the end of the bolt for fastening the block in place.

In testimony whereof I affix my signature.

CLEMENT H. RITZLER.
